UNITED STATES PATENT OFFICE.

ARTHUR E. KRAUSE, OF MOUNTAIN LAKES, NEW JERSEY.

RECORD CONTAINER.

Application filed July 17, 1920. Serial No. 396,939.

To all whom it may concern:

Be it known that I, ARTHUR E. KRAUSE, a citizen of the United States, residing at Mountain Lakes, in the county of Morris and 5 State of New Jersey, have invented an Improvement in Record Containers, of which the following is a specification.

This invention relates to a record container and more particularly to the construction of a record container by which the same is fitted with an edge or end portion adapted to carry an inscription to indicate the contents of the container. The invention is particularly adapted for use in envelope 10 containers constructed to contain phonograph records, although obviously its use is not limited to this specific purpose inasmuch as it may be applied to any relatively flat container designed to hold records of any 15 character whether stored on edge or in superimposed positions. Difficulty and much inconvenience is generally experienced in storing phonograph records as well as records of various other types in relatively flat envelopes because as commonly employed no 20 means are provided for indicating the contents of any particular wrapper or envelope and it is therefore necessary to withdraw each envelope from the pile in order to examine its contents in finding any particular record that may be desired, and the object of 25 my invention is to overcome this difficulty.

In carrying out the invention, I preferably employ an envelope or wrapper which is 30 constructed in the usual manner with exception that along one edge the same is provided with a reinforcing strip or other means to cause this edge to be flattened to a predetermined extent preferably to the width 35 or approximate width of the article or records to be stored in the container and in any event of a sufficient width to enable the user to apply an inscription to this flattened edge of the envelope which is readily observable 40 and consequently may be read by the user while the envelope is in its pile irrespective 45 of whether the envelopes and their contents are stored or maintained in a superimposed pile or are made to stand on edge as is customary 50 in storing phonograph records. Also in the particular use to which I apply the invention the flattened edge of the envelope, as hereinbefore stated, is preferably of approximately the same width as the thickness 55 of the record so that the records when stored or placed in position in the cabinet present a

uniform appearance in substantially the same manner as books arranged on a shelf, and by suitably inscribing the flattened edge of the envelope with the title of the record, 60 or other inscription, any record is as readily available from the record cabinet as any particular book is available and may be found from a book shelf.

The invention will be hereinafter more 65 particularly described in conjunction with the accompanying drawings, in which,—

Fig. 1 is a perspective view of a record container made in accordance with this invention and particularly adapted to receive 70 and store phonograph records.

Fig. 2 is a cross section on line 2—2, Fig. 1.

Fig. 3 is a cross section on line 3—3, Fig. 1.

Fig. 4 is a perspective view showing the application of the invention to an ordinary 75 form of envelope.

Fig. 5 is a cross section on line 5—5, Fig. 4.

Fig. 6 is a partial cross section showing a modified form of the invention, and

Fig. 7 is a cross section showing the end 80 member as used in the form of the invention shown in Fig. 6.

Referring to the drawing and particularly to Figs. 1 to 3 inclusive, the envelope with which the present invention is particularly adapted for use is indicated at 10. This is the usual form of envelope adapted to receive and contain phonograph records and comprises oppositely disposed substantially parallel members 11 and 12 which are open 85 along one edge as indicated at 13 and ordinarily closed with sharp edges at the other edges of the envelope. In this instance the sides of the envelope 11 and 12 may be provided as is customary with the openings 14 90 through which the inscription on the phonograph record may be read without removing the record from the envelope and the edge 15 as well as the edge 16 are the customary sharp edges as generally employed in envelopes 95 of this nature, the edge 15 being opposite the edge which is open to receive the record. Along the edge opposite the sharp edge 16, however, I preferably employ a reinforcing strip or member 17 which may be made of relatively heavy paper board or sheet metal 100 or other similar material which will answer the purpose and over which this edge of the envelope is folded to make the same a flat instead of a sharp edge. The width of the 110 reinforcing strip is substantially the thickness of the phonograph record so that when

- placed in the envelope the edges of the flattened end of the envelope will lie in substantially the same planes as the oppositely disposed sides of the phonograph record.
- 5 When constructed for this use or otherwise the flattened edge of the envelope is of sufficient width, as will be understood, to have placed thereon an inscription which will indicate the record contained in the envelope.
- 10 While I have herein described the use of the reinforcing strip 17, it will be understood that in some instances the edge or one end of the envelope may be so constructed as to be suitably flattened without the employment 15 of this reinforcing strip, although the use of the reinforcing strip is advisable because of the strength it adds to the envelope in which it is employed.

By reference to Figs. 4 and 5, it will be seen that the invention may be utilized in an ordinary form of envelope adapted to contain legal documents or other papers to be stored or filed away and in this structure the envelope is indicated at 19 and one flap 25 thereof, as for instance the flap 20, may be so constructed as to be folded over and secured to a reinforcing strip 21 so as to provide the envelope at one end or along one edge thereof with a flattened edge 22 adapted to receive the necessary inscription to indicate the contents of the envelope wrapper or container.

By reference to Figs. 6 and 7, it will furthermore be understood that the invention 35 may be practiced by applying a suitably covered reinforcing strip to the edge of an ordinary phonograph record envelope or other similar container. In such an instance the reinforcing strip is indicated at 23 and is 40 provided with a cover 24 extending over and secured to one face thereof and reaching appreciably beyond the edges of the reinforcing strip so that the ends 25 thereof extend sufficiently far from the edges of the reinforcing strip to be suitably applied by adhesive or in any other manner to the opposite members 26 of an envelope or other container. It will be apparent that the inner faces of the cover 24 may be provided with 45 glue or other adhesive so that by the mere application of moisture this form of end or edge member may be applied to an ordinarily

constructed envelope wrapper or container and will provide the necessary flattened edge to carry an inscription to indicate the contents of the container. 55

It will be understood that in all events the parts of the flattened edge are caused to assume the position which is substantially at right angles to the oppositely disposed walls 60 or cover members comprising the container and that the flattened edge may be made by suitably folding a part of the walls of the container or by folding the same over the reinforcing strip as hereinbefore described or 65 otherwise within the scope of the appended claims without departing from the nature and spirit of my invention.

I claim as my invention:

1. A phonograph record container comprising a rectangular envelope having oppositely disposed substantially parallel walls with three edges of the envelope being sharp edges, in one of which there is an opening, and a reinforcing strip secured along the 75 fourth edge of the envelope at substantially right angles to the walls thereof to provide a fixed flattened edge adapted to receive an inscription to indicate the contents of the container. 80

2. A phonograph record container comprising a rectangular envelope having oppositely disposed substantially parallel walls, with three edges of the envelope being sharp edges, in one of which there is an opening, and a reinforcing strip placed in the envelope along the fourth edge thereof at substantially right angles to the walls of the envelope to provide a fixed flattened edge 85 adapted to receive an inscription to indicate the contents of the container. 90

3. A phonograph record container comprising a rectangular envelope having oppositely disposed substantially parallel walls with three edges of the envelope being sharp 95 edges, in one of which there is an opening, and a reinforcing strip extending along the fourth edge of the envelope at substantially right angles thereto to provide a flattened edge adapted to receive an inscription to 100 indicate the contents of the envelope.

Signed by me this 7th day of July, 1920.

ARTHUR E. KRAUSE.
